UNITED STATES PATENT OFFICE.

JOSEPH RYDER BEE, OF LEEDS, ENGLAND, ASSIGNOR TO FAIRBAIRN LAWSON COMBE BARBOUR LIMITED, OF LEEDS, ENGLAND.

DRIVING MECHANISM FOR THE SPINDLES OF SPINNING AND LIKE MACHINES.

Application filed January 28, 1925, Serial No. 5,247, and in Great Britain April 8, 1924.

In driving the spindles of spinning, doubling, twisting and like machines, it is essential from time to time as is well known to arrest or stop the motions of said spindles 5 to enable the attendant to repair broken threads and perform other operations.

Under ordinary conditions during such stoppage the driving tape or band is continually running around and slipping over 10 the surface of the pulley or wharle on the driving spindle and thus causes great wear and deterioration of said parts.

My present invention consists in the production of improved means whereby I am 15 enabled to permit the wharle or driving pulley mounted upon the spindle to run loosely, when the attendant operates my improved devices for arresting the motion of the spindle, and that under such conditions that 20 whether the spindle is being rotated in one direction or the other the same effective manipulation of said spindle is secured while the application of my improved devices not only arrest motion of the spindle by its engaging with the driving pulley but also enables the application thereto of a brake so 25 that such stoppage is more quickly effected.

In the accompanying sheets of drawings 30 illustrative of my invention:—

Fig. 1 is a sectional elevation showing my improved devices applied to the spindle of a spinning machine (when driven by a belt or tape), with the parts in position where the driving belt would transmit motion 35 thereto.

Fig. 2 is a similar view to Fig. 1 but only shows sufficient thereof to illustrate the positions of the several parts when the driving is suspended.

Fig. 3 is a plan of parts shown by Fig. 1.

Fig. 4 is a similar view to Fig. 1 (drawn to a reduced scale) to illustrate my improved devices in connection with toothed gearing for transmitting motion thereto.

Fig. 5 is a sectional elevation of the devices shown by Fig. 4 but shows the parts in the relative positions when driving is suspended.

Fig. 6 is a plan of the parts shown by Fig. 4.

In the several parts hereunto annexed I have shown only a portion of the spindle 2 as said spindle is of well known formation and forms no part of my invention.

In carrying my invention into effect I fix 55 upon the spindle 2 a disc 3 so that upon this disc a driving pulley 4 in accordance with the arrangement shown by Figs. 1 to 3 may run loosely thereon or it may run loosely upon a sleeve 5 taking over the surface of 60 the spindle 2 to prevent wear. This pulley 4 as stated is supported by and runs loosely upon the disc 3 which is fixed to the spindle 2 and the upper surface of this pulley 4 is prepared by having fixed to it any frictional 65 material as leather or the like 6 so that same may contact with another similarly prepared surface 7 formed upon a disc 8 which takes loosely over the spindle 2 and preferably with a flange 8^a taking into a groove 70 in the upper end of the pulley 4. This disc 8 has the upper surface of its hub formed with a series of inclined parts 9 and these inclined surfaces are formed to correspond to inclined surfaces 10 made upon the lower 75 edge of the collar 11 which is also fixed upon the spindle 2.

Spanning the upper edge of the driving pulley 4 and beneath the disc 8 is an operating fork 12 pivoted upon a shaft 13 and actuated by any appropriate devices connected with the connecting rod 14, thus as the rod 14 raises the fork lever 12 it will raise the disc 8 so that its friction surface 7 is clear of the friction surface 6 formed on the pulley 4. 85

The positions where the two surfaces 6 and 7 are in contact with each other is shown by Fig. 1 while in Fig. 2 the surfaces 6 and 7 are shown apart from each other. When the fork lever 12 descends or is removed from supporting the disc 8 this latter descends so that its surface 7 will be in contact with the surface 6 on the pulley 4. Thus the rotary motions of said pulley which are transmitted to it by the belt or tape 15 immediately 90 commence to revolve the disc 8 and as this disc 8 is thus revolved its inclined surfaces 9 are caused to engage or come against the inclined surfaces 10 on the collar 11. Thus a wedging action is set up and the greater 95 the force acting upon the disc 8 and its inclined surfaces 9 so will the force of these inclined surfaces 9 against the inclined surfaces 10 increase the friction effect of the surface 7 against the surface 6 by which arrangement I secure a drive which is practically positive although it is only secured by the friction surfaces described. 100 105

The forming of the friction surfaces 6 and 7 upon the upper end of a driving member 4^a and upon the disc 8 are carried out according to the arrangement shown by Fig. 4 in connection with the spindle 2, but in this case the friction surface 6 is secured to the upper surface of the flange 4^b on a sleeve 4^a which has a toothed wheel 4^c formed at its lower end. Thus the toothed wheel has its teeth of screw or helical formation to gear with similar or correspondingly formed teeth in the driving wheel 16 and this driving wheel 16 is mounted upon the shaft 17 that is rotated in well known manner in other types of spindle driving gear. In the embodiment of the invention illustrated in Figures 4 to 6, the lever 12 is provided with an extension beyond the shaft 13, on which is mounted a weight that counterbalances the lever arm and the operating devices connected thereto through the rod 14. The other parts of my devices as hereinbefore described with reference to Figs. 1 to 3 are the same and act in the same manner in connection with the devices shown and described by reference to Figs. 4 to 6 of the drawings as they do in the former arrangement.

Such being the nature and object of my said invention, what I claim is:

- 30 1. The combination with a substantially vertical spindle of a spinning or like machine, of a driving member supported on the spindle by means permitting it to rotate relative to the spindle, a disc loosely surrounding the spindle above the driving member and adapted to be rotated by frictional contact between its lower face and said member, a collar secured to the spindle and engaged with said disc to transmit power from the driving member to the spindle as the disc rotates in either direction, the parts being so related as to permit movement of the disc longitudinally of the spindle to disconnect the disc from the driving member without disengaging it from said collar, means for rotating the driving member, and means independently movable longitudinally of the

spindle for lifting the disc from frictional engagement with the driving member.

2. The combination with a substantially vertical spindle of a spinning or like machine, of a collar secured to the spindle, a driving member loosely surrounding the spindle and supported by said collar, a disc loosely surrounding the spindle above the driving member and having a depending hub extending into the upper end of the bore in the driving member, the adjacent faces of the disc and driving member being adapted to make frictional contact, whereby the disc may be rotated by the driving member, a second collar secured to the spindle above the disc and having a serrated lower face engaging the disc to transmit power to the spindle as the disc rotates in either direction, the parts being so related that the disc may be moved from frictional engagement with the driving member without affecting its connection with said second collar, means for rotating the driving member and means for lifting the disc from engagement with the driving member.

3. The combination with a substantially vertical spindle of a spinning or like machine, of a driving member supported on the spindle by means permitting said member to rotate relative to the spindle, a disc loosely surrounding the spindle above the driving member and adapted to be rotated by frictional contact with said member, a collar secured to the spindle and engaged by said disc to transmit power from the driving member to the spindle as the disc rotates in either direction, the parts being so related as to permit movement of the disc on the spindle to disconnect the disc from the driving member without disengaging it from said collar, means for rotating the driving member, a forked lever having its arms extending on opposite sides of the driving member beneath said disc, and means for rocking said lever to lift the disk from frictional engagement with the driving member.

JOSEPH RYDER BEE.
